EINAR A. JOHNSEN, OF MOUNTAIN LAKES, NEW JERSEY, ASSIGNOR TO ENGINEERING DEVELOPMENT COMPANY, OF NEW BRUNSWICK, NEW JERSEY, A CORPORATION OF NEW JERSEY.

CONDENSER.

Application filed January 7, 1927. Serial No. 159,517.

My present invention relates to a condenser and more particularly to a surface condenser of the multiple pass type. The particular feature to which the invention relates is the provision of devices self contained in a multi-pass surface condenser for reversing the direction of the flow of the circulating medium through the condenser tubes without reversing the direction of the flow of the circulating medium as the same is delivered by the means for moving the same. The efficiency of a surface condenser depends largely upon the coefficient of heat exchange between the steam to be condensed and the circulating cooling medium. This in turn is dependent largely upon maintaining a uniform quantity of flow of the circulating medium through the condenser tubes and also upon the condition, that is the cleanliness of the tubes. These conditions are believed to be self evident. In condenser practice it is necessary in order to maintain a desired vacuum and at the same time to operate the circulating pump or pumps at their normal capacities, that is without overloading the pumps, to clean the condenser and the tubes thereof at more or less frequent intervals. The frequency with which it is found necessary to clean the condenser and its tubes depends upon operating conditions. In many places the water available for circulating purposes, particularly at certain seasons of the year, contains almost all kinds of refuse, débris and other foreign substances which clog the condenser tubes, and the circulating water may also contain various chemical substances which have a tendency to form a scale or to otherwise clog the space in the tubes and to thus affect the conditions of the tubes to the detriment of the heat transfer coefficient. Condenser tubes have been cleaned in various manners, for example by the use of a sand blast, by forcing plugs through the tubes, and by using metal brushes for scraping the tubes, as well as in various other and similar manners. I am aware that heretofore it has been recognized that condenser tubes may be cleaned by reversing the flow of the circulating medium in order that any refuse which may have collected on the tube sheets or lodged within the tubes may be removed and also that the formation of scale may be

obviated to some extent. In reversing the direction of the flow of the circulating medium, however, it is necessary that the piping system be more or less involved and made to include a multiplicity of valves so that the necessary piping is not only more or less complicated, but occupies so much space and is so relatively costly as to make the practice substantially prohibitive.

The reversal of the direction of the flow of the circulating medium for the purposes of cleansing the condenser and the tubes thereof is undoubtedly more effective in the use of a single pass condenser than it is the use of a multiple pass condenser. Nevertheless, the reversal of the direction of the flow of the circulating medium may be used advantageously for cleansing purposes in a multi-pass condenser, and the present invention relates more particularly to the construction of a multi-pass condenser within which, so that the condenser is a self contained unit, means are provided for reversing the direction of the flow of the circulating medium without changing the direction of the flow of the circulating medium as delivered by the pump or pumps employed to move the same.

In carrying out my present invention the condenser made in accordance therewith is preferably constructed to form a two pass condenser in which and preferably in one of the water boxes means are provided for directing the flow of the circulating medium to either of the banks of tubes, and means are also provided for the discharge of the circulating medium from this water box whereby the positions of the means for directing the flow of the circulating medium may be so adjusted as to reverse the direction of the flow of the circulating medium through the banks of tubes in the condenser without changing the direction of the flow of the circulating medium from the pump or pumps supplying the same. In this type of condenser it is also preferable to employ a suitable baffle plate so constructed that in normal operation the larger portion of the incoming exhaust steam is directed toward the cooler end of the condenser tubes. The condenser constructed in accordance with my present invention will be hereinafter more particularly described in conjunction

- with the accompanying drawing in which Figure 1 is a plan of a condenser made in accordance with the invention, and Fig. 2 is a section on line 2—2, Fig. 1.
- 5 Referring to the drawing the shell of a surface condenser is indicated at 10. In the customary manner the end portions of the condenser shell are flanged as indicated at 11 and 12 and provided with tube plates 13 and 14, together with water boxes 15 and 16. The water boxes and tube plates are connected to the flanges at the ends of the condenser shell in the customary manner. The condenser shell is provided in any suitable 15 position with a steam inlet which as illustrated is at the top of the condenser and designated at 17. Within the condenser shell and extending between and connected at their ends in the tube plates there are 20 series or banks of tubes 18 and 19. Furthermore, and also as is customary, the water box 15 is provided with a bonnet or cover 20 and the water box 16 with a bonnet or cover 21.
- 25 In a suitable position the water box 16, which in this construction is the inlet and outlet water box, is provided with inlet connections 22 and 23 for a circulating medium. In the inlet connection 22 there is a 30 valve 24. This may be a valve of any desired type, and as illustrated, is what may be termed a flap valve mounted on a shaft 25 which is journaled in bearings provided therefor in the walls of the water box. At 35 its peripheral portion the valve 24 is adapted to bear against a seat 26 formed in a rib 27 also in the walls of the water box. The shaft 25 extends through the cover 21 and exteriorly thereof is fitted with a gear or hand wheel 28 by means of which the shaft 40 may be turned to determine the position of the valve 24.
- 45 In a similar manner the inlet connection 23 is provided with a valve 29. This valve is preferably similar to the valve 24 and is mounted on a shaft 30 which is journaled in bearings provided therefor in the walls of the water box. The valve 29 is adapted to bear against a seat 31 formed in a rib 32 also in the walls of the water box. The shaft 30 passes through the cover 21 and exteriorly thereof is fitted with a gear or hand wheel 33 by which the shaft may be turned 50 to determine the position of the valve 29.
- 55 The water box 16 is provided with a transverse partition wall 34. As illustrated, this partition wall is placed in a substantially vertical position when the condenser is set for use, although as will be understood this 60 partition wall may assume any position depending upon the positions of the inlet and outlet connections to and from the water box. In a centrally disposed position substantially midway between the inlet connections the water box is provided with an out-

let connection 35. In this outlet connection or adjacent thereto the water box is fitted with a valve made in angular form, the parts of which are indicated at 36 and 37. This valve is mounted on a shaft 38 which is journaled in bearings provided therefor in the walls of the water box and the shaft extends through the cover 21 and exteriorly thereof is fitted with a gear or hand wheel 39 by means of which the shaft may be turned to determine the position of the parts 70 36 and 37 of this valve. The peripheral portion of the part 36 of this discharge valve is adapted to bear against a seat 40 formed in a rib 41 in the walls of the discharge connection. Similarly the peripheral portion of the part 37 of the discharge valve is adapted to bear against a seat 42 formed in a rib 43 in the walls of the discharge connection of the water box. 85

In the use of the condenser as hereinbefore described, the water or other circulating medium employed may be taken from any suitable source of supply and caused to flow through a supply line 44 by means of a pump 45 driven by a motor 46 or otherwise, the discharge end of the pump being connected to the supply line by a pipe 47 in which there is a valve 48. It will be understood that any necessary number of these 90 circulating pumps to meet the requirements of any given installation may be employed. The supply line 44 is provided with a branch 49 which is connected to the inlet nozzle 23 and the supply line is extended as indicated at 50 so as to have one end thereof connected to the inlet connection 22. Connected to the discharge connection 35 there is a pipe 51 leading to a discharge line 52. In normal operation the valves in the inlet 105 connections and the discharge connection are set as illustrated in Fig. 2 of the drawing. The circulating medium caused to flow by the pump 45 will therefore pass to the inlet connection 22 inasmuch as the valve 24 is open and thence to the left hand compartment in the water box as illustrated in this figure through the tubes 18 in the tube bank A to the water box 15 which is constructed to have a unitary chamber, thence in the opposite direction through the tubes 19 in the tube bank B to the outlet connection 35 and to the discharge line 52. To effect a reversal of the flow of the circulating medium the valve 24 is closed, the valve 29 is 110 opened, and the discharge valve is placed with the parts thereof in the position in which the part 37 bears against the seat 42 whereby as will be understood the circulating medium caused to flow by the pump 45 will pass to the inlet connection 23, thence to the right hand compartment of the water box 16 as viewed in Fig. 2, through the tubes 19 in the tube bank B to the water box 15, thence through the tubes 18 in the tube 115 120 125 130

bank A to the discharge connection 35 and the discharge line 52, the circulating medium thus passing in the opposite direction through the banks of tubes.

5 In this type of condenser it is preferable to employ a suitable baffle at or adjacent the exhaust steam inlet in order to divert or direct a relatively large proportion of the incoming exhaust steam to the cooler end of 70
10 the condenser tubes. Such a form of baffle plate is indicated at 53 and may be made of sheet metal so curved as to have a substantially vertical portion 54 at one end thereof and an inclined portion 55 at the 13 other end thereof. This baffle plate as will be understood may be mounted in any suitable manner and made in any suitable configuration to effect its intended purposes.

20 It will be understood that the baffle plate 53 functions as stated to direct the greater portion of the incoming exhaust steam to the cooler ends of the condenser tubes when the apparatus is operating under normal conditions in which the direction of the flow of the cooling medium through the tubes is indicated by the arrows in Figure 1, and that while the baffle plate does not function as stated when the direction of the flow of the 25 cooling medium is reversed, the period during which the flow of the cooling medium is reversed for the purpose of cleaning the tubes is so relatively short that the fact that the baffle plate does not then operate 30 as intended will not materially affect the operation of the apparatus.

It will now be understood that the condenser as hereinbefore described is a multi-pass condenser of the two pass type and that 40 by the use of the valve devices in the inlet and outlet connections of the water box at one end of the condenser the reversal of the direction of the flow of the circulating medium may be effected without a complicated system of pipes and valves. Furthermore, that by relatively frequent reversals 45 of the direction of the flow of the circulating medium for more or less short intervals of time the condenser tubes may be maintained in such a condition as to make the condenser operate in an efficient and satisfactory manner.

I claim as my invention:

1. In a two pass surface condenser, a 55 shell, banks of tubes therein, a water box at one end of the shell, means shiftable within the water box for directing the flow of a circulating medium to a predetermined bank of tubes, and means also shiftable in 60 the water box for controlling the discharge of the circulating medium therefrom whereby the circulating medium may be directed to pass in one direction through one bank of tubes and in another direction through another bank of tubes and by

shifting the position of the said means the circulating medium may be directed to flow in the opposite direction through the last aforesaid bank of tubes and in the opposite direction through the first aforesaid bank 70 of tubes.

2. In a two pass surface condenser, a shell having an opening therein for the admission of exhaust steam to be condensed, banks of tubes in the shell, means at one end of 75 the condenser for controlling the admission of a circulating medium to the banks of tubes, means at the same end of the condenser for controlling the discharge of the circulating medium therefrom, and a baffle plate within the shell and adjacent the said opening therein for the exhaust steam and adapted to deflect the larger portion of the incoming exhaust steam through the cooler 80 end of the condenser tubes.

3. In a two pass surface condenser, a shell having an opening therein for the admission of exhaust steam to be condensed, banks of tubes therein, a water box at one end of the shell, means in the water box for directing the flow of a circulating medium thereto, means in the water box for directing the flow of a circulating medium from the condenser, and a baffle plate within the shell and adjacent the said opening therein 90 for the exhaust steam and adapted to deflect the larger portion of the incoming exhaust steam through the cooler end of the condenser tubes.

4. In a two pass surface condenser, a shell having an opening therein for the admission of exhaust steam to be condensed, banks of tubes in the shell, a water box at one end of the condenser, a transverse partition wall dividing the water box into two oppositely disposed compartments, inlet connections each leading to one of the compartments in the water box, valves in the inlet connections for controlling the passage of a circulating medium to either compartment 100 in the water box, a discharge connection common to both compartments in the water box, a valve for controlling the discharge of the circulating medium through the said discharge connection, and a baffle plate 105 within the shell and adjacent the said opening therein for the exhaust steam and adapted to deflect the larger portion of the incoming exhaust steam through the cooler 110 end of the condenser tubes.

5. In a two pass surface condenser, a shell, banks of tubes therein, means at one end of the condenser for admitting a cooling medium to either one of two banks of tubes whereby the cooling medium passes in one direction through one bank of tubes and in the opposite direction through the other bank of tubes, a common discharge connection for the said banks of tubes, and means for controlling the passage of the 115 120 125 130

cooling medium from either bank of tubes to the said discharge connection.

6. In a two pass surface condenser, a shell, tubes therein, a water box having a partition wall dividing the same into two compartments communicating with two banks of tubes, a separate inlet connection to both the said compartments for a cooling medium, a common outlet connection from the said compartments, and means for controlling the direction of the flow of a cooling medium to either compartment from its inlet connection and from the other compartment by way of the common outlet connection.

7. In a two pass surface condenser, a shell, tubes therein, a water box at one end of the condenser having a partition wall dividing the same into two compartments, separate inlet connections for cooling a medium to the said compartments, a common outlet connection from the said compartments, means in the said inlet connections for controlling the passage of the cooling medium therethrough and to the corresponding compartment in the water box, and means in the outlet connection for making communication between one compartment and the outlet connection and for closing communication between the other compartment and the outlet connection.

8. In a two pass surface condenser, a shell, tubes therein, a water box having a partition wall dividing the same into two compartments, an inlet connection for a cooling medium to one of the said compartments, a valve in the said inlet con-

nection for controlling the flow of the cooling medium to the said compartment, an inlet connection for a cooling medium to the other compartment, a valve in the second inlet connection for controlling the passage of the cooling medium to the second compartment, a common discharge for the cooling medium from either of said compartments, and means in the discharge connection for opening communication between one compartment and the discharge connection and closing communication between the other compartment and the discharge connection.

9. In a two pass surface condenser, a shell, tubes therein, a water box having a partition wall dividing the same into two compartments, an inlet connection for a cooling medium to one of the said compartments, a valve in the said inlet connection for controlling the flow of the cooling medium to the said compartment, an inlet connection for a cooling medium to the other compartment, a valve in the second inlet connection for controlling the passage of the cooling medium to the second compartment, a discharge connection common to both said compartments, and a valve in said discharge connection adapted to open communication between either of the said compartments and the discharge connection and simultaneously to close communication between the other compartment and the discharge connection.

Signed by me this 22nd day of December, 1926.

EINAR A. JOHNSEN.
